DESIGN FOR A DRESSER FOR GRINDING WHEELS OR THE LIKE

Henry C. Stoll, Jackson Heights, N. Y.

Application March 15, 1944, Serial No. 112,913

Term of patent 14 years

(Cl. D37—1)

To all whom it may concern:

Be it known that I, Henry C. Stoll, a citizen of the United States, residing at Jackson Heights, Queens County, and State of New York, have invented a new, original, and ornamental Design for a Dresser for Grinding Wheels or the like, of which the following is a specification, reference being had to the accompanying drawing, forming part thereof.

Fig. 1 is a front elevation of a dresser for grinding wheels or the like, showing my new design;

Fig. 2 is an end view, and

Fig. 3 is a top plan view thereof.

I claim:

The ornamental design for a dresser for grinding wheels or the like, substantially as shown.

HENRY C. STOLL.
